UNITED STATES PATENT OFFICE.

HARRISON D. McFADDIN, OF EAST ORANGE, NEW JERSEY.

LIGHTING-FIXTURE.

1,188,548.

Specification of Letters Patent. Patented June 27, 1916.

Application filed January 28, 1915. Serial No. 4,815.

To all whom it may concern:

Be it known that I, HARRISON D. McFADDIN, a citizen of the United States, residing in the city of East Orange, county of Essex, 5 and State of New Jersey, have invented a certain new and useful Lighting-Fixture, of which the following is a specification.

This invention is a lighting fixture of a character particularly adapted for use in 10 connection with a semi-direct lighting unit, and the object of the invention is to support a lamp shade in a simple, attractive and efficient manner.

The invention permits of ready access to 15 the interior of the shade for the purpose of cleaning it, or replacing the lamp, and, when desired, the shade may be readily removed from the supporting fixture and its coöperating attaching devices.

20 Speaking generally, the invention embodies lamp-supporting means provided with members adapted to maintain the weight of a globe or shade, and a member for detachably gripping said shade, said member being preferably retained in its operative gripping position by the means which supports the shade on the fixture.

It will be noted that the device is exceptionally simple and economical to manu- 25 facture.

In the preferred practical embodiment of the invention, an annular member is provided, adapted to engage with the usual peripheral flange on the shade or globe, and to 30 this annular member are secured a plurality of supporting elements adapted to engage with attaching devices on the fixture for supporting the globe beneath, and in proper relation to, the source of light.

35 A salient feature of the invention resides in the fact that one of the supporting elements coöperates with the annular member in such manner as to lock the same in clamping position upon the globe, and such element is adapted to be manipulated to unlock the annular member to allow of the removal of the globe from the fixture.

40 Features of the invention, other than those specified, will be apparent from the following specification read in conjunction with the accompanying drawings.

45 In the accompanying drawings, I have illustrated one practical embodiment of the present invention, but the construction shown therein is to be understood as illus-

trative, only, and not as defining the limits of the invention.

Figure 1 is a side elevation of a lamp fixture embodying the present invention, the parts thereof being shown in their operative 60 positions. Fig. 2 is a similar view of the fixture, with the globe tilted to allow of cleaning the interior thereof. Fig. 3 is a fragmental section taken on line 3—3 of Fig. 1. Fig. 4 is a fragmental, plan view of 65 the annular member with the globe detached, said annular member being shown in its closed and locked position, and Fig. 5 is a view similar to Fig. 4, with the free ends of the annular member unlocked and parted 70 to allow of the removal or replacement of the globe.

Referring to said drawings, A indicates a fixture of any common and well-known type, provided with a socket a, into which is 75 adapted to be screwed the plug of an electric bulb B. The fixture is, moreover, provided with a plurality of globe-supporting devices, shown in the drawings as three hooks c, which are stationary with the fixture. 80 These hooks serve as the primary carrying elements of the globe.

The globe is designated by the reference numeral D, and, while shown semi-spherical in shape, may be of any shape or contour desired. Globe D is provided at its upper edge with the usual laterally extending, peripheral flange d, by which it is adapted to be supported.

According to the present invention, an 90 annular member E is provided, which is adapted to engage with the peripheral flange d of the globe, and this annular member or ring is preferably of metal, its function being when in engagement with flange d, 95 to provide means whereby suitable supporting devices may be employed to sustain the weight of the globe. In the preferred embodiment of the invention shown, ring E is channeled in cross-section and is parted at 100 one side to allow it to be positioned on, or removed from, globe D. Its free ends are adapted to overlap one another when the ring is in contracted operative position in engagement with the globe, and means is 105 provided for locking these ends in overlapped relation. Ring E is supported in relative position to the fixture and below the lamp by means of a plurality of chains, links, or bars e, the upper ends of which are 110

provided with eyes adapted to engage with the hooks *c*, and the lower ends of which are provided with hook *e'* adapted to be passed through apertures *f* in the upper portion of the channeled ring *E*. Links *e* thus serve as a support for ring *E* and the globe embraced thereby. It will be noted, from Fig. 1, that two apertures *f* are positioned near the free ends of the ring and are of such distance therefrom that, when the free ends of the rings are overlapped, these two apertures will come into alignment. If the hook *e'* of one of the links *e* is passed through said aligned apertures, when the ends of ring *E* are in overlapped relation, this hook will serve to lock the parts together after the manner clearly shown in Fig. 3. The remaining apertures *f* are spaced at proper distances around the ring *E*, and with each of these apertures co-
operates a link *e*.

It will thus be manifest that, of the several links which operate to support the globe, one of them serves a dual purpose, viz., it supports the globe and simultaneously locks the ring *E* in its clamped or closed position. This obviates the necessity of independent fastening devices and makes the fixture of the present invention extremely simple, yet, withal, highly efficient. By virtue of the simple manner in which the links are secured to fixture *A*, they may be readily detached therefrom by simply loosening their upper ends from their respective hooks *c*. However, when it is desired to clean the interior of the globe, it is only necessary to loosen one of the links *e*, whereupon the portion of the globe supported by said link will sag or drop and thereby cause the globe to tilt into the position shown in Fig. 2, while the same is supported on the remaining links *e*. When in the position shown in Fig. 2, access may be readily had to the interior of the globe without detaching the same from the fixture and, when the cleaning operation is finished, the globe may be restored to its initial, normal position by simply rehooking the upper end of the link *e* over its corresponding hook *c*.

As heretofore stated, ring *E* is preferably channeled in cross-section, and this insures against the inadvertent falling forward of the globe, when in the position illustrated in Fig. 2, should said globe tilt to a greater angle than that shown, it being manifest that, when the locking link is in place, ring *E* serves as a binding for the upper portion of the globe and is locked thereon against removal in any direction until the link in question is removed from the aperture *f*.

When it is desired to remove globe *D* from ring *E*, the link *e*, which engages with the aligned apertures *f*, is detached from the hook *c* of the fixture and is swung outwardly

into substantial alignment with the top edge of the globe, whereupon the shifting of said link toward the center of the globe, as shown in dotted lines in Fig. 3, will cause the hooked end *e'* of said link to become disengaged from ring *E*, with the result that the ends of said ring are unlocked and are allowed to part, as shown in Fig. 5. The globe may now be removed. In replacing the globe, the reverse of the foregoing operation is carried out.

It will be manifest, from the foregoing description, that the device of the present invention is extremely simple, yet absolutely positive in its operation. The globe, when locked to ring *E*, cannot become detached and fall out, either in its normally closed position or in its position for cleaning. This is an important feature, from the standpoint of the user.

The separate elements which combine to make up the combination are, in themselves, simple and very economical to manufacture, all milling, threading, and other expensive mechanical operations being dispensed with, and these elements are of such construction that nothing can possibly get out of order, even through a long period of use.

I have described and shown the preferred embodiment of the invention, although it will be manifest that slight changes may be made, from time to time, in adapting the invention to various types of fixtures, either gas or electric. Moreover, ring *E* may be decorated or formed in artistic manners, and may, if desired, be of other than channeled cross-section, such, *e. g.*, as L-shaped. Furthermore, if a polygonal-shaped globe is desired, it will, of course, be understood that ring *E* will be made of corresponding shape in contour. I, therefore, wish it understood that I do not restrict the present invention to the precise structure described and shown, but consider my invention as broadly new as commensurate with the appended claims.

It will be noted that, in the construction described, it is not necessary to drill or perforate the globe, as is the case with many of the supporting devices now employed. Moreover, the supporting ring and wire links not only avoid excessive shadows, but reduce the shadow effects to a minimum.

Having thus fully described the invention, what I claim as new, and desire to secure by Letters Patent, is:—

1. In a device of the class described, means for gripping a lamp globe, and a supporting member formed at one end with means for engaging a fixed support and at its other end with means for securing the gripping member on the globe, whereby said supporting member maintains the globe and its gripping member in operative relation and simultaneously supports the globe and gripping member.

2. In a device of the class described, the combination of a parted ring for detachably gripping a lamp globe, supporting devices for sustaining the weight of said globe, said supporting devices coöperating with a lamp supporting fixture and also locking the parted ring in its gripping position.
3. In a device of the class described, the combination with a parted ring, the free ends of which are overlapped to detachably grip a lamp globe, of connections for supporting the weight of said globe, said supporting connections being adapted to coöperate with a lamp-supporting fixture and also to lock the parted ring in its gripping position.
4. In a device of the class described, the combination with a parted ring, the free ends of which are overlapped to detachably grip a lamp globe, of supporting connections secured to said ring and adapted to engage with a lamp-supporting fixture to maintain the globe in a predetermined position relative to the lamp, one of said supporting connections being secured to the ring at the point of overlapping of the free ends thereof, whereby said connection locks the ring in its clamping position on the globe.
5. In a device of the class described, the combination with a parted ring, the free ends of which are overlapped to detachably grip a lamp globe, of supporting connections secured to said ring and adapted to engage with a lamp-supporting fixture to maintain the globe in a predetermined position relative to the lamp, one of said supporting connections being adapted to extend through apertures in the overlapped free ends of the ring for the purpose of locking the ring in its clamping position on the globe.
6. In a device of the class described, the combination with a lamp supporting fixture, of a parted ring for gripping a lamp globe, and spacing links secured to the lamp supporting fixture at one of their ends and to the parted ring at their other ends, one of said spacing links simultaneously coöperating with both ends of the parted ring for locking the same on the globe.
7. In a device of the class described, a ring adapted to engage with the peripheral flange of a lamp globe, said ring being parted to allow of its positioning on, or removal from, the lamp globe, the free ends of said ring being adapted to overlap when the ring is in engagement with the globe, and a plurality of supporting devices spaced about said ring and adapted to engage with the supporting means on the fixture, one of said supporting devices being adapted to also engage with both of the overlapping ends of said ring when said ends are in overlapped relation, for the purpose of locking the ring upon the globe.
8. In a device of the class described, the combination with a lamp-supporting fixture, of a parted ring adapted to grip a lamp globe when the free ends of said ring are in overlapped relation, links provided at their lower ends with hooks extending through spaced apertures in said ring and adapted, at their opposite ends, to coöperate with the lamp-supporting fixture for the purpose of supporting the weight of the globe, the hook at the end of one of said links also passing through apertures in both of the overlapped ends of said ring whereby the ring is locked in its gripping position on the globe.
9. In a device of the class described, the combination of a lamp supporting fixture, a gripping member adapted to embrace a lamp globe, and supporting members, each of which is secured to the globe gripping member at one end and to the lamp supporting fixture at the other end for maintaining the globe in predetermined position relative to the lamp and also locking the globe gripping member on the globe.
10. In a device of the class described, a globe supporting member embracing the upper edge of a lamp globe, and a lamp fixture, in combination with a plurality of weight-carrying members, each of which is secured at one end to the fixture and at the other end to the globe supporting member for mounting the globe supporting member on the fixture, and means formed on one of said weight-carrying members for locking the globe supporting member to the globe, the weight-carrying member specified being detachable from the lamp fixture to allow of access to the interior of the globe, its associated locking means serving to lock the globe to the supporting member when said weight-carrying member is in engagement with, or disengaged from, the fixture.
11. In a device of the class described, a globe supporting device, a securing member for locking said device to a globe, and means, formed on the securing member, for attaching it directly to a lamp fixture, said securing member being adapted to lock the supporting device to the globe whether the attaching portion of said member is in engagement with, or disengaged from, the lamp fixture.

In testimony whereof I have signed my name to this specification in the presence of two subscribing witnesses.
